United States Patent Office

Des. 214,155
Patented May 20, 1969

214,155

SHOE ORNAMENT

Etienne Aigner, New York, N.Y., assignor to Villager Industries, Inc., a corporation of Delaware

Filed Sept. 18, 1968, Ser. No. 13,596

Term of patent 14 years

Int. Cl. D2—04

U.S. Cl. D2—315

Fig-1

Fig-3

Fig-2

FIG. 1 is a front elevational view of a shoe ornament, showing my new design;

FIG. 2 is a top plan view thereof; and

FIG. 3 is a side elevational view.

I claim:

The ornamental design for a shoe ornament, substantially as shown.
